(57) **CLAIM**

The ornamental design for a sliding dimmer switch, as
shown and described.

DESCRIPTION

FIG. 1 is a front perspective view of a sliding dimmer switch
according to an exemplary embodiment of the present
disclosure;

FIG. 2 is a front view of the sliding dimmer switch of FIG.
1;

FIG. 3 is a back view of the sliding dimmer switch of FIG.
1;

FIG. 4 is a first side view of the sliding dimmer switch of
FIG. 1;

FIG. 5 is a second, opposite side view of the sliding dimmer
switch of FIG. 1;

FIG. 6 is a top view of the sliding dimmer switch of FIG. 1;
and,

FIG. 7 is a bottom view of the sliding dimmer switch of FIG.
1.

The broken lines in the drawings illustrating environmental
structure or boundaries that form no part of the claimed
design.

1 Claim, 6 Drawing Sheets
